THE NORRIS PETERS CO., PHOTOLITHO., WASHINGTON, D. C.

UNITED STATES PATENT OFFICE.

LOUIS GERÖ, OF BUDA-PESTH, AUSTRIA-HUNGARY.

PAPER-FEEDING MACHINE.

SPECIFICATION forming part of Letters Patent No. 618,409, dated January 31, 1899.

Application filed May 15, 1897. Serial No. 636,821. (No model.)

To all whom it may concern:

Be it known that I, LOUIS GERÖ, a subject of the King of Hungary, and a resident of the city of Buda-Pesth, Austria-Hungary, have 5 invented certain new and useful Improvements in Automatic Paper-Feeding Devices for Printing-Presses, of which the following is a specification.

Many forms of automatic paper-feeding devices for steam printing-presses have proved unserviceable because they raised with the top sheet of the pile the sheet immediately adhering thereto and carried them along for a greater or less distance toward the printing-cylinder, and thus caused interruption of work.

In these machines the following defects occur: First, the paper sheet is seized on too large a surface, so that the adhesion between 10 the first sheet and the second and third sheets under it can take effect; second, the paper sheet is carried along on the next sheet while it is taken off, and thereby the second sheet is displaced; third, the sheet must travel too 15 far to reach the printing-cylinder, whereby either the work becomes slower or when the feeding is quickened the lifting becomes so sudden that two or more sheets are carried along; fourth, the pneumatic gripper is in 20 constant motion, so that the lower sheet when carried along is given no time to fall back on the paper pile; fifth, although devices for holding down the pile automatically have 25 been employed they are in no organic connection with the feeding appliance, whereby the 30 disadvantage arises that the sheet which has been lifted along and returned to the paper pile cannot be brought again under the contrivance which effects the holding down, and 35 therefore the sheet lies loosely, and, sixth, finally, there are constructions in which the 40 suction-pipes make suitable movements, but seize the lowest sheet of the paper pile, so that the whole weight of the latter will rest on the 45 sheet to be pulled out.

The most essential disadvantages of this arrangement are that the feeding of single sheets is not assured and that, on the other hand, the sheet pulled from under the pile is 50 under strong tension and therefore tears easily. My object is to avoid all these objections.

In the drawings, Figure 1 shows the general arrangement of the device in side view with parts in section, wherein all parts not 55 pertaining to the present invention are omitted. Fig. 2 is a plan view of Fig. 1, partly in section. Fig. 3 shows in diagram the suction-cylinder and the parts for effecting partial return rolling of same in the position in which 60 the top sheet is taken from the paper pile. Fig. 4 shows in detail the position of the suction-cylinder after it has rolled back in its guiding-frame for the purpose of delivering the sheet which has just been taken off to the 65 printing-cylinder. Fig. 5 is a section along the line 5 5 of Fig. 1, looking in the direction of the arrow. Fig. 6 shows a hook which holds down the paper pile and the setting appliance of the hook in perspective. Fig. 7 70 shows in detail the crank arranged on the axle of the suction-pipe and the tappet effecting its turning over.

The feeding-table *a*, Fig. 1, is arranged near the printing-cylinder, so that the sheet to be 75 laid in *c*, Fig. 3, will have to travel as short a distance as possible. The table is automatically raised by means of parallel links *d* and a weighted lever *2*, linked to the table, and this movement takes place each time the 80 paper is taken from the top of the pile *s*. The pile is held on the table in such a manner that no sheet can be displaced during the work. For this purpose angle-irons *g*, of suitable 85 height, are arranged at both sides of the paper pile, Fig. 2, and in the horizontal flanges of same cross-slits *g'* are provided, through which the screw-bolts *g*² pass to fasten the angle-irons on the frame. These slits *g'* allow a lateral adjustment of the angle-irons to 90 suit any width of paper sheets.

At the rear side of the paper pile hooks *h* are arranged, Fig. 1, which are fastened on arms *h'* of the machine-frame in such a manner that the table can move freely under them 95 and that the surface of the paper pile is always kept in close contact with them. In order to adapt these hooks to the length of the paper, slits *h*² are provided in the hooks, as shown clearly in Fig. 6, so that the hooks 100 can be adjusted by loosening the nuts *h*² and fastened within the limits allowed by the length of the slits.

At the front of the paper pile holding-down

- 5 fingers i are arranged for the purpose of holding the paper pile, Figs. 1 and 2. These holding-down fingers are fastened on double-armed levers j' , pivoting around the pinion j^0 .
 10 The double-armed levers are linked with levers j , which are moved by a curved disk j^0 , keyed on the shaft n' in such a manner that the holding-down fingers i can be raised from the paper pile and laid on it again.
 15 The suction-pipe k has a round cross-section of suitable form and has a suitable number of free spaces o , Fig. 2, which correspond with the grippers p of the printing-cylinder and the holding-down fingers i of the paper pile.

20 The axle-journals k' of the suction-pipes k pivot in blocks k^2 , and these blocks are set into rectangular slideways l . The hollow journal k' extends beyond the block k^2 and carries at its free extremity the toothed wheel u , the toothed wheel f^0 , and the crank-lever v . The rack v^0 is fastened under the frame l , and it gears with the toothed wheel u , while the toothed wheel f^0 can be engaged with the segment f . This segment is set on one arm of 25 the angle-lever, pivoted at f' , the other arm of which is actuated by the cam-disk r , keyed on the shaft n' . The frame l and all parts mounted thereon are carried by one arm of 30 the angle-lever m , pivoted at m' , the other arm being linked to the bar n^0 , actuated by the cam n .

35 The suction-pipe k is bedded eccentrically in relation to its axle $k' k'$, and its suction-holes are situated nearly on the edge of the spaces o . The suction-pipe will then lie upon the top sheet in such a manner that its suction-holes are at the front edge of the sheet. The particular advantage of the eccentric 40 bearing of the suction-pipe is to be found in the fact that when it is turned in the direction of the arrow 1, Fig. 1, after having seized a sheet the latter will not only be drawn along, but it is also taken off in the measure 45 of the suction-pipe's eccentricity, thus avoiding a displacement of the sheets under the top sheet.

50 The axle-journals k' of the suction-pipe are hollow and are connected by a hose q with an air-pump of known construction, which is omitted from the drawings. A three-way cock x is inserted in this hose q , Fig. 1, the plug of which is turned away by means of levers from the cam y , keyed on the main shaft in 55 such a manner that it connects the hose q either with the pump or by the pipe-socket z with the atmosphere.

60 The device works in the following manner: Supposing that the suction-pipe k be just placed on the front edge of the top sheet, which is still held down by the holding-down fingers i and hooks h , the air is now pumped from the suction-pipe through the hose q , whereby the top sheet lays itself on the suction-holes of the suction-pipe k , as above referred to, at the same time the cam j^0 actuates the angle-lever i' through the rod j in

70 the manner that the holding-down fingers i are raised from the paper pile in Fig. 1, while, on the other hand, the cam r moves the segment t from right to left by means of angle-levers t^2 into the position shown in Fig. 3, whereby the toothed wheel t^0 , which is in engagement with the segment t , is turned in the direction of the arrow 1, Fig. 1. The toothed 75 wheel turns the axle k' and therewith the toothed wheel u , which is thereby forced to run along the rack v^0 , and moves the suction-pipe during its revolution over the paper pile, the revolution being caused by segment t and toothed wheel t^0 . Thereby the top sheet c is pulled out from under the hook h and placed on the suction-pipe for some short distance, Fig. 3. Then a moment of rest occurs to give the second next sheet that may have been 80 lifted along time to fall back on the paper pile. In the meantime the cam n , with its eccentric part, has reached out and takes the frame l with the suction-pipe k and the seized sheet c away from the paper pile by 85 means of the bar n^0 and the angle-lever m and carries it to the printing-cylinder b .

90 The preliminary lifting of the frame l is advantageous, because the toothed wheel t^0 is thereby disengaged from the segment t , and the suction-pipe will remain at the right-hand end of the frame l with its gear in mesh with the rack n^0 , and the pipe will remain in this position until its crank strikes the tappet w , as will hereinafter be described. As soon 95 as the segment t is released from the toothed wheel t^0 it is pulled back to its starting position by the spring f acting upon the lever f^2 , while the hooks fall back at the same time and hold the paper pile down again. While 100 rolling back on the paper pile the suction-pipe has arrived into the position k' , Fig. 7, and the crank keyed on the extremity of its shaft has reached the position v' , Fig. 7. Now 105 the suction-pipe, with its frame, is moved 110 around the pivot-center m' toward the printing-cylinder, and in this movement the crank, as indicated by the line I, strikes the tappet w , so that the crank is turned over during 115 the forward movement of the frame and remains with its extremity on the upper surface of the tappet w in the position v'' , in which the suction-pipe delivers the sheet to the catchers of the printing-cylinder. Owing 120 to this turn of the crank v the toothed wheel u has been rolled back on the rack v^0 by the same distance as formerly in consequence of the engagement of toothed wheel f^0 and segment t . In other words, the suction-pipe is 125 rolled back in its bearings in the manner that the edge of the sheet seized by it is situated below and can be taken up by the grippers p . After this has been done the suction-pipe, with the crank, as indicated in the lines II III, is 130 guided back to the pile in the same position correspondingly to the frame l . At the moment when the suction-pipe k has reached the printing-cylinder the disk y stops the cock x . The latter stops thereby the way to the pump

and lets the atmospheric air pass into the suction-pipe *k* through the upright tube *z* and the hose *q*, so that the suction-pipe releases the sheet and delivers it to the printing-cylinder. The frame *l*, with the suction-pipe *k*, is moved back to the paper pile and the operation as described is repeated.

I claim—

1. In combination with the table having the holding-down fingers at front and hooks at the rear, a suction-pipe *k* having openings or spaces thereon for the holding-down fingers, means for raising and lowering and turning the suction-tube to lift the top sheet, and means for causing a dwell in the movement of
- 10
- 15

said tube to allow the sheets of the pile to settle down and means for operating the front catches, substantially as described.

2. In combination, the table, the suction-tube having eccentric journals, the gearing on the said journals and the segment *t* and rack *u*⁰ engaging the same, substantially as described. ²⁰

In witness whereof I have hereunto set my hand in presence of two witnesses.

LOUIS GERÖ.
